VACUUM CLEANER

Filed March 19, 1929

UNITED STATES PATENT OFFICE

RUBIN BASS, OF BROOKLYN, NEW YORK

VACUUM CLEANER

Application filed March 19, 1929. Serial No. 348,206.

My invention relates particularly to hand operated apparatus embodying a brush and suction mechanism.

One object is to provide a construction which is very compact and yet reliable and convenient to use.

Another object is to provide convenient means for removing and replacing the brush.

In its preferred form I provide a casing containing an electric motor and a suction fan together with a brush driven from the shaft of the motor. The brush and motor shafts are at approximately right angles to each other and connected by a quarter turn belt. A part of the brush is exposed in a suitable manner and one wall of the casing is made removable so as to permit convenient access to the brush and to the pulleys and belt. One form of the invention is shown and claimed in my Patent 1,711,132, in which the bottom wall is removable and provided with openings for the brush. The form shown and specifically claimed herein has the rear wall removable and may also have the bottom wall removable. By this rearrangement it becomes more convenient to assemble the brush and belt and to remove the same. This also provides a bearing surface so disposed with respect to the casing and its handle as to facilitate the use of the device on a small and irregular surface.

Fig. 1 is a side view and partial section of one form of apparatus embodying my invention.

Fig. 2 is a rear view of the same with the cover plate removed.

Fig. 3 is a fragmentary view looking upwardly to show the suction mouth and brush.

Fig. 4 is a fragmentary sectional view of a modification. Fig. 5 is a sectional view of the cover plate adapted to the casing of Fig. 4.

Fig. 6 is a detail view of the brush and belt.

The casing 7 may be of suitable material and preferably contains an electric motor 8 and a suction fan 9. The casing has an extension or suction chamber 10 at its rear end with an inlet mouth 11 at the bottom. The handle 12 may conveniently serve as a pas-

sage for the discharge of the dirt which is loosened and sucked up by the device.

The brush 13 may be of any suitable type having bristles suitably secured in a shaft 14 positioned in open ended bearing seats or bearing sockets 15 in opposite side walls of the chamber. The shaft is provided with a pulley 16 which in this form is arranged in the approximate center of the shaft. The shaft 17 which extends from the motor is provided with a pulley 18 which is connected to the pulley 16 by a quarter turn belt 19.

Prior to my invention the belts in devices of this character have been formed of rubber so as to be sufficiently elastic to permit the replacement of the brush and the attachment of the belt. According to my invention, however, this belt 19 may be made of leather or any other suitable durable and flexible material. The bottom of the chamber is preferably provided with a cross bar 20 beneath the pulley 16 on the brush shaft so as to prevent the pulley from coming in contact with the goods.

The rear end of the chamber is open so as to allow convenient access to the interior thereof for the purpose of inserting the brush and the belt and to facilitate the removal of the same. In this connection I provide a cover plate 21 which is detachably secured to the chamber, preferably with tight joints so as to avoid leakage around its edges. Preferably the cover will be secured at the bottom 22 and the upper edge at 23.

The bottom wall 24' in which the suction openings 11 are located may also be removable and may be formed as a part of or integral with the rear part 25, as shown in Fig. 5. The casing for such a construction would of course be open at the rear and also at the bottom, as shown in Fig. 4. Such a construction provides an opening 26 at the bottom and an opening 27 at the rear so as to even more facilitate the insertion of the brush and the attachment of the belt. The cover is now formed of the walls 25 and 24' and is releasably secured to the casing by means of hooks 28 and 29 or other suitable means.

I claim:

1. A vacuum cleaner comprising a handle member, a casing mounted on the upper side of the handle member and having an extension at its lower end extending below the handle member, said extension having an opening at its lower end transverse to the length of the handle member and having an opening at the rear end, a motor supported in the casing with its axis parallel to the handle member and having a pulley on one end of the motor shaft, a brush detachably mounted in the extension in position for its bristles to project through the bottom opening, a quarter turned belt connecting the pulley with the brush and accessible through the rear end opening of the casing extension and a cover plate closing the rear end opening in the casing, said brush and belt being completely exposed and removable through said rear end opening when the cover is removed.
2. A vacuum cleaner comprising a casing having a rearward and downward extension, said extension including bottom, side and rear walls forming a chamber, a motor mounted in the casing, said extension having open ended bearing seats on the opposite side walls, a rotary brush having a shaft detachably supported in said bearing seats in said chamber adjacent its bottom wall, a belt operatively connecting said motor and said brush, said rear wall and said bottom wall having openings, said brush having a portion projecting through the bottom opening, and a plate detachably mounted on said extension and adapted to cover the opening in said rear wall.

RUBIN BASS.
